UNITED STATES PATENT OFFICE.

ALFRED JOHN GREAVES, OF RICHMOND, ENGLAND.

RECEPTACLE FOR MUSTARD AND OTHER CONDIMENTS.

1,024,988.

Specification of Letters Patent.

Patented Apr. 30, 1912.

Application filed October 28, 1911. Serial No. 657,350.

To all whom it may concern:

Be it known that I, ALFRED JOHN GREAVES, a subject of the King of Great Britain, residing at 3 Townshend Terrace, Richmond, 5 late 45 Rye Hill Park, Peckham Rye, both in the county of Surrey, England, have invented certain new and useful Improvements in or Relating to Receptacles for Mustard and other Condiments, of which 10 the following is a specification.

This invention relates to receptacles for mustard and other condiments, and has for its object to provide a receptacle or device of such a character that a limited quantity 15 of the contents may be ejected or obtained therefrom while enabling the bulk of the substance to be preserved in usable condition for a longer period than is possible with apparatus or containers heretofore ordinarily proposed or employed.

For the purpose of the present description it will be assumed that the apparatus or device is to be used in connection with mustard, which, after being mixed for 20 table use, has the property of separating out to a certain extent.

The apparatus or device according to the present invention is therefore designed with a view to counteracting the inconveniences 25 arising from the aforesaid tendency to separation and, to this end, the device comprises a receptacle which is adapted to receive a piston or plunger whereby the contents are forced for the purpose of expelling 30 the same. The watery portion is also brought into admixture with the thicker portion, the two portions being subjected to a commingling so that waste is avoided and a better mixing insured.

40 In order that the said invention may be clearly understood and readily carried into effect, I will proceed to describe the same with reference to the accompanying drawings, in which:—

45 Figure 1 is a vertical section illustrating a receptacle for use with mustard embodying the present invention. Fig. 2 is a similar view illustrating another construction which also embodies the features of the 50 present invention. Fig. 3 is a view of the plunger and spindle detached from the receptacle and drawn to a larger scale for clearness. Figs. 4 and 5 are a partial sectional elevation and a plan view respectively

of a modified form of the device illustrated 55 in Fig. 2.

The device consists of a receptacle *a* which communicates with a chamber *l* of a more or less annular character and adapted to communicate with the delivery pipe or nozzle *e*. A valve chamber *d* is arranged at the inner end of the nozzle and between the same and the aforesaid annular chamber *l*. The nozzle *e* is provided with a spring controlled valve *f* so that when the material is 60 forced through the chamber *d* the said valve is unseated against the resistance of the spring *f'* and the quantity that is forced into the discharge chamber is ejected 65 through the nozzle. The valve *f* is formed 70 with longitudinal vanes *f²* and the spindle carries a conical portion *f³* which is acted upon by the pressure of the material when the plunger *g* is actuated as hereinafter described. The outer extremity of the valve 75 is disk shaped and fits into the mouth of the nozzle. The plunger *g* is provided with perforations *g²* which are opened and closed by a disk or valve *g³* loosely mounted on the rod *g⁴* pertaining to the said piston or plunger. The upper end of the rod *g⁴* is housed 80 in a stem *g⁵* depending from the knob *g⁶* a washer ring or disk *g⁷* being provided for retaining the said knob in the lid or cover *a'*. The chamber *l* may comprise a cylindrical member *l'* having a suitable opening or suitable openings *l²*, such as lateral slots, gaps or spacings at the lower end, the said member being provided with spiral, curved or other conveniently formed vanes *l³* 85 adapted to occupy the space between the cylindrical member *l'* and the inner surface of the receptacle or shell *a*, and constitute a chamber or conduit, or chambers, or conduits, whereby the material, which is 90 forced by the piston or plunger *g*, is conducted to the valve chamber *d* and thence to the nozzle *e*.

Referring particularly to Fig. 3, the piston or plunger *g* is carried by a hollow rod 100 or tube *m* wherein is mounted a hollow tubular member *m'*. The bore *m²* of this latter member is open to the contents of the receptacle by means of cross cuts *m³*, *m⁴* or other devices but subject to control by 105 means of a ball or other valve *m⁵*. The hollow rod or tube is formed with lateral perforations or ports *m⁶* so that liquid pass-

ing up the bore m^2 of the inner tube m' may find an exit to the receptacle. The inner tube is controlled by a spring shown at m^7 and actuated by means of a button or 5 equivalent device g' provided in the lid or cover a' of the receptacle. Upon depressing the button g' , the plunger g is forced down, whereupon any watery liquid is forced by way of the bore m^2 in the inner tube m' 10 and cross cuts m^3 through the lateral perforations or ports m^6 , into this receptacle a to mix with the bulk of the material therein. Thus a frequent mixing effect is obtained by bringing the said watery liquid 15 from the lower end of the receptacle to the top of the material contained in the receptacle. The upper part of the receptacle a may be adapted to receive a removable lining a^x which may be constructed of glass, 20 plated metal or other material affording a surface capable of being readily cleansed. The aforesaid lateral perforations or ports m^6 may be situated at any suitable height above the piston or plunger g and it will 25 be apparent that the inner hollow tubular member m' has the effect of closing the said ports when the device is operated by depressing the piston or plunger with the aid of the knob or handle g' . A disk or per- 30 forated plate n may be arranged above the piston or plunger g for the purpose of indicating the level of the material so that a fresh supply may be charged into the apparatus and the efficient working of the 35 latter preserved. This plate will serve as an ordinary depth gage and is normally immersed in the material and its appearance above the level thereof will indicate that the receptacle needs recharging.

40 If desired, the bottom or lower end of the receptacle or the aforesaid cylindrical member may communicate with a space or funnel o arranged at the lower end of the apparatus as shown in Fig. 2, a discharge 45 valve p being provided in the said space or funnel so that upon the depression of the piston or plunger a certain quantity of the contents of the receptacle is ejected as in the previously described arrangement, but 50 in this instance the discharge takes place from the lower end while in the earlier arrangement the exit is from the side. The valve illustrated in Fig. 2 comprises a spring controlled plunger p' which projects 55 beyond the funnel shaped extremity of the receptacle a . This plunger is formed with longitudinal slots and wings p^2 and takes a seating on the bushing shown at p^3 . Upon 60 pressing the projecting portion p' against a surface such as that of a plate, for instance, the plunger recedes with the result that the slots and wings dispose themselves opposite the lateral openings p^4 and allow of the passage through the nozzle of the 65 material from the space o .

In the construction adapted for end discharge the receptacle a may be formed with an exterior circumferential ridge or projection (not shown) so as to enable the device to be supported in a stand or cruet; or the device may be arranged for being supported by means of feet, legs or equivalent contrivances or a suitable device may be used and which may be of cup formation.

The outlet valve may be subject to control either by pressure of mustard as hereinbefore described or by direct communication with the piston or plunger. In the latter case, the valve may be arranged for actuation by a spring controlled bolt, whereof 75 the operating end projects into the path of the piston or plunger or into the path of an arm pertaining thereto. Such an arrangement is shown in Figs. 4 and 5 in which the funnel shaped extremity o of the casing 80 a is provided with a valve s similar in construction to the valve employed in the arrangement illustrated in Fig. 1. The receptacle is provided with a partition s' in which are formed raised portions or ridges 85 s^2 having perforations or openings s^3 formed at their crests or upper ends. One of the ridges s^2 is provided with an opening s^4 which is adapted to receive a rod or bolt 90 s^5 . This bolt is provided with an arm or 95 extension s^6 which engages with the stem s^7 of the valve s , the upper extremity of the bolt s^5 is arranged to engage with the piston or plunger in the receptacle. When 100 the piston or plunger is depressed the material is first mixed in the manner previously described and then forced through the openings s^3 into the space or funnel o , and as the depression of the piston has operated the bolt s^5 , the valve s will be open to 105 allow of the material being discharged.

What I claim and desire to secure by Letters Patent of the United States is:—

1. In a receptacle for mustard and other condiments the combination of a hollow bi-part rod and a piston carried by said rod which is adapted to mix the material by forcing the liquid portion thereof from the lower to the upper part of the receptacle through said hollow bi-part rod and to eject 110 a quantity of the material.

2. In a receptacle for mustard and other condiments the combination of a hollow bi-part rod, an outlet valve and a plunger carried by said bi-part rod which is adapted to 115 mix the material by forcing the liquid portion thereof from the lower to the upper part of the receptacle through said hollow bi-part rod and then eject a quantity of the material through said outlet valve.

3. In a receptacle for mustard and other condiments the combination of a hollow bi-part rod, a pressure operated valve and a plunger carried by said bi-part rod which is 120 adapted to mix the material by forcing the 125 material through the nozzle of the 130

liquid portion thereof from the lower to the upper part of the receptacle through said hollow bi-part rod and then eject a quantity of the material past said pressure operated valve.

4. In a receptacle for mustard and other condiments the combination of a tubular member, a piston secured to said tubular member, a spring controlled hollow member 10 inclosed within said tubular member and adapted to be moved relatively thereto to place the lower and upper parts of the receptacle in communication during the first part of the movement of the piston and to 15 interrupt such communication during the final stage of the movement of the piston.
5. In a receptacle for mustard and other condiments the combination of a hollow bi-part rod, a plunger secured to said rod, a 20 disk loosely mounted on said rod and acting in conjunction with said plunger and bi-part rod to mix and discharge the material contained in the receptacle.
6. In a receptacle for mustard and other

condiments the combination of a hollow bi- 25 part telescopic rod, a plunger secured to said rod, a disk loosely mounted on said rod which on the operation of the aforesaid rod is first adapted to act in conjunction with the plunger to mix the material and finally 30 discharge the same from the receptacle.

7. In a receptacle for mustard and other condiments the combination of a hollow bi-part rod, a plunger secured to said rod, perforations in said plunger, a disk loosely 35 mounted on the bi-part rod and serving to open and close the perforations in the plunger, a nozzle, and a valve in proximity to said nozzle which is adapted to be operated to discharge the material when it is subjected to a predetermined degree of pressure.

In testimony whereof I affix my signature in presence of two witnesses.

ALFRED JOHN GREAVES.
